CLAIM

The ornamental design for a decorative floor and table top heater, as shown and described.

DESCRIPTION

FIG. 1 is a right front perspective view of the decorative floor and table top heater showing our new design;
FIG. 2 is a left front perspective view thereof;
FIG. 3 is a right rear perspective view thereof;
FIG. 4 is a left rear perspective view thereof;
FIG. 5 is a left side view thereof;
FIG. 6 is a right side view thereof;
FIG. 7 is a front view thereof;
FIG. 8 is a rear view thereof;
FIG. 9 is top perspective view thereof; and,
FIG. 10 is a bottom view thereof.

The broken-line disclosure in the views is for illustrative purposes only and forms no part of the claimed design.
